UNITED STATES PATENT OFFICE.

STEPHEN MEERS, OF BROOKLYN, NEW YORK.

APPARATUS FOR MAKING ARTIFICIAL LEATHER.

1,235,043.

Specification of Letters Patent. Patented July 31, 1917.

Application filed March 13, 1907, Serial No. 362,152. Renewed June 22, 1917. Serial No. 176,427.

To all whom it may concern:

Be it known that I, STEPHEN MEERS, a citizen of the United States, residing at the city of New York, borough of Brooklyn, and State of New York, have invented a certain new and useful Apparatus for Making Artificial Leather, of which the following is a specification.

This invention is an apparatus employed 10 in the manufacture of artificial leather.

As is well known, artificial leather is now extensively used as a substitute for the natural product, the said artificial leather consisting, as a rule of a fabric, to which has 15 been applied one or more coatings of various materials, and among which are solutions of nitrocellulose in volatile and other solvents.

After the fabric has been coated it is 20 most important that the same be expeditiously and uniformly dried, and this invention accomplishes these objects in a most satisfactory manner.

Furthermore, the apparatus is so constructed that after the first coating is applied to the fabric and the latter passed through said apparatus for the purpose of drying said coating, a second, or as many 25 coatings as desired, may be superimposed 30 on the first coating without any winding or unwinding of the fabric or without removing it from the apparatus.

The drying must be effected while the fabric is under proper tension, lengthwise 35 of the fabric, and, also, while said fabric is kept from wrinkling laterally.

The apparatus comprises a substantially closed chamber, provided with means for supporting and effecting the passage of the 40 artificial leather therethrough in a circuitous path, means for producing a circulation of heated air within the chamber, and other devices and appliances incident to the performance of said functions, such as means 45 for keeping the leather at a proper tension, spreading it laterally, etc.

In the accompanying drawings, I have illustrated one practical embodiment of the invention, but the construction shown there- 50 in is to be understood as illustrative only, and not as defining the limits of the invention.

Figure 1 is a vertical longitudinal section through the apparatus for making artificial 55 leather embodying this invention, the plane of the section being indicated by the dotted

line 1—1 in Fig. 2 looking in the direction of the arrow.

Fig. 2 is a horizontal section on the line 2—2 of Fig. 1.

Fig. 3 is a vertical section on the line 3—3 of Fig. 1, showing certain other parts in elevation.

Fig. 4 is a detail view showing parts of the apparatus in side elevation.

Fig. 5 is an enlarged detail sectional view of a carriage forming a part of the tension mechanism for the web of material to be treated.

Fig. 6 is a plan view of the tension mechanism shown in Fig. 5.

Fig. 7 is a detail view showing one form of air heater adapted to be used in connection with the fan or blower.

Fig. 8 is a detail view through one of the blast pipes showing a delivery slot therein.

A designates a casing of the apparatus, which casing may be of any appropriate size and shape. The casing provides a drying chamber, A', which is closed at the sides, 80 ends and top. In one end wall of the casing is a horizontal slot, a, which provides for the ingress of a web of material, X, said slot being at or near to the upper portion of the casing. In the other end wall 85 of the casing is another slot, a', which is close to the floor or bottom of the apparatus and permits the egress of said web of material.

Within the drying chamber, A', is situated a plurality of devices which are adapted to support and guide the web of material in a circuitous path, said chamber containing, also, means whereby the web of material is kept under tension lengthwise and is spread laterally for the purpose of overcoming any tendency of the material to wrinkle, crease or fold during the operation of drying the materials applied to the web in the treatment of the fabric.

B designates a guide roller or cylinder which is arranged in the chamber near one of the corners thereof, the upper surface of said roller being in the horizontal plane of the slot, a. This roller is mounted on a shaft, b, which is journaled in appropriate bearings, b', as shown in Fig. 3, and one end of this shaft extends beyond the casing for the reception of a driving pulley, B', and a transmission pulley, B². The driving pulley is operated by a belt, B³, indicated by dotted lines in Fig. 3, said belt being op-

erated from a line shaft, a motor or any other source of power.

In the upper part of the drying chamber, A', is a horizontal partition, C, which extends from the front wall of the casing, A, to a point quite close to the roll, B. This partition forms a compartment, c, in the upper part of the drying chamber, and into this compartment the web, X, is first conducted. From the upper part of the casing, A, extends a stack or uptake, D, which provides an outlet for the hot air and vapors from the apparatus. Below the port or opening which establishes communication between the stack or uptake and the compartment, c, of the drying chamber is a movable valve or plate, d, which is kept in position by suitable guides, d', the latter suspending the valve or plate at a point above the web of material and normally in a position to permit the hot air and vapor to escape from the drying chamber into the stack.

E, E' designate other rolls for supporting and guiding the web of material, X, said rolls being at the opposite end of the drying chamber from the roll, B. The rolls, E, E', are supported in a suitable way within the drying chamber, and they are arranged one below the other, the roll, E, being in a horizontal plane below the roll, B.

F designates a roll which is in a horizontal plane between the rolls, E, E', and is adapted to be supported at different distances from the rolls, B, E, E'. The roll, F, coöperates with the other rolls of the series in supporting and guiding the material, but said roll, F, is supported by adjustable tension devices within the drying chamber in order that webs, X, of different lengths may be held under proper tension within the apparatus. The roll, F, is carried by a shaft which is mounted in bearings on an adjustable carriage, G. In Figs. 5 and 6 of the drawings a portion of this carriage, G, is shown. Said carriage consists of parallel sides, g, which are connected rigidly by a cross bar, H, the latter being constructed to form one of the spreaders for the web, X. The side members, g, of the tension carriage, G, are provided with the bearings, f, for the shaft of the movable roll, F, but in Figs. 5 and 6 only one of the bearings, f, is shown, and the roll, F, is indicated in dotted lines in Fig. 5. The sides of the carriage, G, are fitted on horizontal rails, g', which are fixed in the chamber, A', at the lower part thereof. Said rails, g', extend longitudinally of the drying chamber, at the respective sides thereof, and the carriage, G, is held in place on said rails so as to be free to move lengthwise of the drying chamber. The carriage is moved or adjusted in the drying chamber by any suitable means, but as shown, I

prefer to employ sprocket chains, I', I', for the adjustment of said carriage. Each chain is connected at one end to a side member, g, of the carriage, and said chain extends forwardly from the carriage substantially parallel to the carriage rails, g'. The two chains are fitted to sprocket wheels, i, on a shaft, I², which is journaled in the front part of the chamber, A', and from the sprocket, i, the chains, I', I', extend rearwardly to and around other sprocket wheels, i', on a shaft, I², the other ends of said sprocket chains being secured to the side members, g, of the carriage. The shaft, I², is journaled in suitable bearings, j, see Fig. 3, and one end of this shaft is extended beyond the side of the casing, A'. Said protruding end of the shaft is provided with a ratchet wheel, J', and with an operating hand wheel, J², a pawl, J³, engaging with said ratchet, as shown in Fig. 4. By turning the hand wheel, J², in one direction the shaft, I², is operated to impart motion to the chains, I', I', for moving the carriage, G, and the take up roll, F, toward the front part of the drying chamber, but when the hand wheel and shaft, I², are turned in the opposite direction, the chains move the carriage and the take up roll toward the rear part of the drying chamber. The ratchet, J', is engaged by the pawl, J³, for holding the shaft, I², against rotation in the direction of the pull on the web, X, on the take up roll, F, whereby the carriage and the take up roll may be adjusted readily to suit the length of the web, X, and operate to keep said web under tension longitudinally.

For the purpose of stretching the web transversely in order to keep it from wrinkling or creasing I employ a plurality of spreaders, K, K', H, within the drying chamber A'. The spreaders, K, K', are supported in stationary positions quite close to the rolls, E, E', whereas the other spreader, H, is mounted on the carriage, G, for movement therewith. Each spreader is provided with a working face adapted to engage with the material of web, X, on the uncoated surface thereof in a manner to strain the fabric of the web crosswise thereof, and to this end each spreader is constructed with a ribbed or corrugated working surface shown more particularly in Figs. 5 and 6 of the drawings, wherein the spreader, H, is represented as having two diagonal rows of corrugations or ribs, h, h'. The corrugations, ribs or other equivalents indicated at h, are inclined oppositely to the corrugations or ribs, h', of the spreader, H, and as the web is drawn across the corrugations or ribs, h, h', of the spreader they operate to stretch the material in opposite directions so as to prevent the web from wrinkling or creasing. It will be under-

stood that each spreader of the number employed in the apparatus has a working face constructed as herein described, and adapted for engagement frictionally with the web, 5 X, of material. The stationary spreaders, K, K', have their working faces in horizontal planes a little below the upper surface of the rolls, E, E', whereby the web of material is adapted to be deflected just before it 10 passes around said rolls. Said spreaders, K, K', are supported in place within the drying chamber by any suitable means, but as shown the spreaders are fastened at their ends to battens, k, which are secured to the 15 respective side walls of the chamber, A', preferably across suitable doors, a², the latter being provided in the side walls of the casing, A, so as to enable an operator to obtain access to the drying chamber, A'. 20 The other spreader, H, is supported on the carriage, G, for its working surface to be above the horizontal plane of the take up roll, F, substantially as shown in Figs. 1 and 5. After the web of material leaves the 25 roll, E', it is carried beneath the carriage, G, and its operating chains in order that the web of material may be extended through the slot, a', and around an exposed guide roll, L, the latter being outside of the drying 30 chamber at the rear part thereof. The shaft of this external guide roller is journaled in bearings of a suitable bracket, l, and on said shaft is secured a gear, m, which meshes with a gear pinion, m', on a countershaft, M. Said countershaft is journaled 35 in suitable bearings on the bracket, l, and it is provided with a pulley, m², around which passes a belt, M', the latter being operated by a pulley, B², on the shaft, b, of the positively 40 driven roll, B, whereby the roll, L, is positively driven by gear connections with the roll, B.

O designates an external frame at the front end of the casing, A. This frame is 45 provided at its upper part with web supporting rollers, o, and with a distributor, O', the latter operating to uniformly distribute the material which is to be applied as a coating to the web, X. It is preferred to 50 mount the distributor, O', in a vertically slotted guide, o', to permit of vertical adjustment of said distributor, and furthermore, the rolls, o, o', are in the same horizontal plane, slightly below the entrance 55 slot, a, of the casing, A. The frame O, is provided with other rolls, o², o³, the former being in the horizontal plane of the exposed driven roll, L, whereby the web of material is adapted to be guided by the rolls, o, o², o³, 60 to and from the casing, A, of the apparatus.

Air is blown into the compartment, c, and the drying chamber, A', by a blower or fan, shown by dotted lines at P in Fig. 3. From this fan leads a wind trunk, P', which extends lengthwise of the casing, A, at one

side of the apparatus, as shown in Figs. 2 and 3. The wind trunk supplies air to two series of branches, p, which extend through one side wall of the casing, A, and are connected with distributing pipes, Q, Q', each distributing pipe being provided with one or more discharge slots, q, shown more clearly in Figs. 3 and 8. The air blast pipes, Q, Q', extend horizontally across the compartment, c, and the drying chamber, A', 70 respectively, and the slots or openings, q, in said pipes are placed in positions to blow air upon the coating which is applied to the web, X. It is preferred to arrange the pipes, Q, of one series above the web, X, as 75 it passes through the compartment, c, of the apparatus, whereas the pipes, Q', of the other series are in a horizontal plane between the spreaders, K, K', within the drying chamber, A', the said pipes, Q', being 80 between two leads of the web, X.

Atmospheric air may be blown by the fan, P, into the drying chamber, A', and the air may be heated before it passes into the fan casing, or I may provide means interiorly of the drying chamber for the purpose of heating the air subsequent to its admission into said chamber, or I may employ the preliminary air heater and the interior heating means conjointly. As shown in Fig. 90 7, the preliminary heater, R, is adjacent to the blower, P, and is connected operatively with the intake thereof for the purpose of heating the air before it passes into the blower, but it is evident that this preliminary heater may be omitted, if desired. 95

One means for heating the drying chamber, A', consists of the steam coils, S. As shown, the apparatus is equipped with two steam coils, one coil being in a horizontal plane below the partition, C, and the other in the horizontal plane of the carriage, G, the two coils being connected by a cross pipe, s. I may, however, dispense with the lower heating coil, S, and the connecting 100 pipe, s. The upper coil, S, is supported by a rack, s', secured in the drying chamber directly below the partition, C, and from the respective ends of this coil, S, extend the pipes, s, s², the latter forming the inlet pipe 105 for the admission of steam from the boiler to the heating coil. 110

The operation of the apparatus is as follows: The web of material, X, is adjusted to the rolls, o, o', and it is adapted to be 115 drawn in any suitable way into the apparatus, A. As one means for drawing the web through the apparatus I may employ a rope or cable fastened to an end portion of the web and leading around the several 120 guide rolls within the chambers, c, A'. The web is first drawn through the chamber, c, to and around the roll, B, thence the web passes below the upper coil, S, and above the pipes Q', so as to extend below the 125 130

1
 spreader, K, and around the roll, E. Said web thence extends horizontally and backwardly from the roll, E, below the pipes, Q', over the distributer, H, and around the 5 take up roll, F. From the last mentioned roll the web passes in a horizontal path below the other spreader, K', and around the roll, E', from whence the web passes backwardly through the slot, a', and around the 10 roll, L. Finally the web passes through the slot, a³, in a horizontal path through the chamber, A², to and around the rolls, o², o³, and thence back to the roll, o. The length of the web having been determined, its ends 15 are connected in any suitable way so as to make the web practically endless, and this operation having been performed, the carriage, G, is adjusted by operating the hand wheel, J², of the shaft, I², so as to move the 20 roll, F, away from the roll, E', in order to stretch the web and place it under the required longitudinal tension. The web is drawn taut around the several rolls, B, E, F, E', L, o², o³, o, which taut condition of 25 the web causes the ribbed surfaces of the spreaders, K, K', H, to have such frictional engagement with the material of the web as to stretch it transversely. The web having been properly adjusted, the machine is in 30 condition for operation and the belt, B³, is started for the purpose of rotating the rolls, B, L, which impart traveling motion to the web, X, the latter moving in the direction indicated by the arrow in Fig. 1. The operator 35 pours a solution on the horizontal upper lead of the web, X, said solution being deposited on the web in front of the distributer, O', the latter operating to uniformly distribute the solution across the web, and 40 the surplus material falling into suitable collecting vessels, t. If desired, a coating machine or appliance may be employed at the receiving end of the web. The coated portion of the web is moved through the 45 compartment, c, and is carried back and forth through the drying chamber, A', and as it is moved through the said chambers, c, A', the coating on the web is subjected to the action of heat and the air blast from the 50 pipes, Q, Q'. As before stated, hot air may be blown into the chambers, and the temperature of the air in the chambers may be increased by the heating coil or coils, S. The hot air and vapors from the chamber, 55 A', are made to circulate toward the rear part of the apparatus and around the roll, B, and thence through the chamber, c, before they can escape through the stack or uptake, D. The web, X, may be passed one 60 or more times through the apparatus, A, for the purpose of drying the coating which is applied thereto, and when the first coating has been dried sufficiently another coating of a different material may be applied to 65 the web so as to superimpose a second coat-

ing upon the first coating, whereupon the web is subjected to the drying and evaporating action of the apparatus by causing the web to move in the manner described through the chambers, c, A'. These operations may be continued indefinitely to apply two, three or more coatings to the web of material, X, and then the material may be removed from the apparatus by cutting it transversely or uncoupling its end portions, after which the material may be wound on a roll or shaft so as to place it in a condition for storage preliminary to using the material for commercial purposes. 70 75

While the apparatus has been particularly described with reference to its use in the manufacture of artificial leather, it will of course be understood that it may be used in various related arts. 80

Having thus fully described the invention, what I claim as new, and desire to secure by Letters Patent is: 85

1. In a fabric coating and drying apparatus, the combination of a substantially closed chamber, means within the chamber 90 for supporting a web of coated material, means within the chamber for spreading the web transversely on the uncoated side of the fabric, and means for heating the chamber. 95

2. In a fabric coating and drying apparatus, the combination of a substantially closed chamber, means within the chamber for supporting a web of coated material, one member of said means being mounted on a movable carriage positioned within the chamber whereby the position of said member may be adjusted by the movement of said carriage for the purpose of placing longitudinal tension on said web, means within the chamber for spreading the web transversely on the uncoated side of the fabric, and means for heating the chamber. 100 105

3. In a fabric coating and drying apparatus, the combination of a substantially closed chamber, a plurality of rolls within the chamber for supporting a web of coated material, a plurality of devices in proximity to said rolls and coöperating therewith for spreading the material transversely, and means for heating the chamber. 110 115

4. In a fabric coating and drying apparatus, the combination of a substantially closed chamber, a plurality of rolls within the chamber for supporting a web of coated material, a plurality of devices in proximity to said rolls and coöperating therewith for spreading the material transversely, means for exerting longitudinal tension on the web, and means for heating the chamber. 120 125

5. In a fabric coating and drying apparatus, the combination of a substantially closed chamber, means within the chamber for supporting a web of coated material, means whereby the web of material may be 130

- repeatedly carried through the chamber for the purpose of drying several successive applications of coating material put thereon, and means for heating the chamber.
- 5 6. In a fabric coating and drying apparatus, the combination of a substantially closed chamber, means within the chamber for supporting a web of coated material, means whereby the web of material may be 70 repeatedly carried through the chamber for the purpose of drying several successive applications of coating material put thereon, means for placing lateral and longitudinal tension on the web, and means for heating 10 the chamber.
- 15 7. In a fabric coating and drying apparatus, the combination of a substantially closed chamber, means within the chamber for supporting a web of coated material, 75 and an adjustable carriage carrying one member of said supporting means and carrying, also, a member for transversely spreading the web, whereby both longitudinal and lateral tension may be placed on the web.
- 20 8. In a fabric coating and drying apparatus, the combination of a substantially closed chamber, means within the chamber for supporting a web of coated material, a stationary member cooperating with the supporting means for spreading the web laterally, and a second member adjustable in a direction lengthwise of the web, for also 80 spreading the web laterally.
- 25 9. In a fabric coating and drying apparatus, the combination of a substantially closed chamber, a dividing partition within said chamber, an inlet for the web above said partition, an outlet for the web below said partition, means for injecting warm 90 air above said partition, means for injecting warm air below said partition, means for spreading the web laterally and adjustable means for placing longitudinal tension on the web.
- 30 40 10. In a fabric coating and drying apparatus, the combination of a substantially closed chamber, and a plurality of members within the chamber for supporting a web of material, a carriage on which one of said members is mounted, said carriage being 100 movable lengthwise of the web whereby it may be adjusted to prevent slack in said web.
- 45 50 11. In a fabric coating and drying apparatus, the combination of a substantially closed chamber, a plurality of members within the chamber for supporting a web of material, a carriage on which one of said members is mounted, said carriage being 105 movable lengthwise of the web whereby it may be adjusted to prevent slack in said web, means for spreading the web laterally, and means for heating the chamber.
- 55 60 12. In a fabric coating and drying apparatus, the combination of a substantially closed chamber, a plurality of members with- 110
- in the chamber for supporting a web of material, a carriage on which one of said members is mounted, said carriage being movable lengthwise of the web whereby said carriage may be adjusted to prevent slack in said 70 web, and a spreading device mounted on said carriage for spreading the web laterally.
13. In a fabric coating and drying apparatus, the combination of a substantially closed chamber, means within the chamber 75 for supporting a web of coated material, a spreader for the coating material positioned outside the chamber, means for spreading the web laterally on its uncoated surface, and means operating on the uncoated surface of the fabric for placing longitudinal tension on the web.
14. In a fabric coating and drying apparatus, the combination of a substantially closed chamber, means within the chamber 80 for supporting a web of coated material, means for introducing air into the chamber, perforated air distributers for directing said air onto the coated surface of the web, and means for heating the air.
15. In a fabric coating and drying apparatus for operating on an endless web of material, the combination of a substantially closed chamber, a horizontal partition within said chamber and extending substantially 90 the entire length thereof, a guide roll at the end of said partition positioned partly above and partly below said partition, supporting rolls below said partition, and means whereby a continuous web may enter the chamber 100 above said partition, be passed into, through and out of the chamber and these operations uninterruptedly repeated.
16. In a fabric coating and drying apparatus for operating on an endless web of material, the combination of a substantially closed chamber, a horizontal partition within said chamber and extending substantially 105 the entire length thereof, a guide roll at the end of said partition positioned partly above and partly below said partition, supporting rolls below said partition, means for heating the chamber, and means whereby a continuous web may enter the chamber above said partition, be passed into, through and out 110 of the chamber and these operations uninterruptedly repeated.
17. In a fabric coating and drying apparatus for treating an endless web of material, the combination of a substantially 120 closed chamber, an ingress slit at one end of said chamber for introducing a web of material to be operated upon, an egress slit at the same end of the chamber through which said fabric passes, supporting and guiding means for the web exteriorly of the chamber, means for passing the web in a circuitous path repeatedly and uninterruptedly through the chamber, and means for heating the air within the chamber.

18. In a fabric coating and drying machine, a substantially closed chamber, ingress and egress slits for a fabric at each end of said chamber, means for guiding and supporting the fabric and moving it repeatedly and uninterruptedly through the chamber, and means for heating the chamber.

In testimony whereof I have signed my name to this specification in the presence of two subscribing witnesses.

STEPHEN MEERS.
